INCANDESCENT ELECTRIC LAMP

Milton Fine, Brooklyn, N. Y.

Application May 23, 1935, Serial No. 23,063

3 Claims. (Cl. 176—27)

This invention relates to new and useful improvements in an incandescent electric lamp.

The invention has for an object the construction of a lamp as mentioned which is provided with a filament or filaments and an arrangement wherein each filament or sections of the filament or filaments may be selectively operated, or operated in groups to render the lamp more adaptable.

Specifically, the invention relates to an arrangement by which different circuits controlling the operation of the different filaments or sections of filaments may be very simply and dependably controlled.

As an object of this invention it is proposed to arrange a pair of contacts on the outer end of a base insulation of the lamp, to provide a circuit from the shell contact to one of said contacts, and to include in series a section of the filament, to provide another circuit from the shell contact to the other of said end contacts and to include in series the other section or sections of said filament, and to arrange one of said contacts movable or flexible, and extending over the other of said contacts and normally out of contact therewith, and adapted to engage the end contact of an electric lamp socket in a normally engaged position in the lamp socket, and when the lamp is further engaged in the socket, to flex and make contact with the other of said contacts.

A further object of the invention is the construction of modifications which are characterized by an adjustable end contact for connecting with one contact or the other contact, or both contacts, for controlling the operation of the lamp in one condition or a second condition, or a third condition.

As another object, the invention proposes the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of an incandescent electric lamp of the type to which the invention is applied.

Fig. 2 is a fragmentary sectional view of the base portion of the lamp shown in Fig. 1.

Fig. 3 is a sectional view of the plug end of an incandescent electric lamp constructed accord-

ing to this invention, to which a schematic wiring of the filament has been added.

Fig. 4 is a bottom elevational view of Fig. 3.

Fig. 5 is a fragmentary sectional view of the plug end of an incandescent electric lamp base constructed according to another embodiment of this invention, to which a schematic showing of the filament has been added.

Fig. 6 is a bottom view of Fig. 5.

Fig. 7 is a perspective view of a lamp showing a further embodiment of the invention.

The incandescent electric lamp, shown in Figs. 1 and 2, comprises a vacuum bulb 10 with an internal support stem 11 and which is mounted on an insulation base 12. The bulb 10 is provided with a filament 13. A shell contact 14 is mounted on the insulation base. A pair of contacts 15, 16 are mounted upon the outer end of the insulation base. A circuit extends from the shell contact 14 to one of said end contacts and consists of a lead 17 attached at the point 17a upon the shell 14 and extending through the support stem 11 and terminating in a pair of branches 17b and 17c connected with diametrically opposite sides of the filament 13. The circuit continues through the filament portions 13a and 13b to the lead 17d which extends through the stem 11 and connects with the terminal 16. Another circuit extends from the shell contact 14 to the end contact 15 and includes the lead 17, the branches 17b and 17c (so far the parts of the second circuit are common to the parts of the first circuit), portions 13c and 13d of the filament, and a lead 17e which extends through the stem 11 and connects with the end contact 15.

The end contact 16 has a flexible head 16a extending over the end contact 15, but normally out of connection therewith. This head 16a is adapted to make electrical connection with the end contact of a conventional electric socket when the lamp is engaged into the socket in a normal position. Furthermore, if the lamp is engaged in a second position in the socket, one in which it is screwed further in, or one in which it is engaged further in, then the flexible head 16a is flexed inwards so as to make electrical connection with the end contact 15.

The operation of the device is as follows:— When the lamp is engaged in an electric socket in its normal condition, the circuit including the filament sections 13a and 13b will be in operation so that these filament sections are functioning. If these filament sections break, it is possible to place the lamp in the second condition so that the circuit through the filament

sections 13c and 13d is now in operation. Another use for the lamp would consist in using the lamp in the second position even though no portion of the filament is broken so that the 5 candle power of the lamp is increased, as all portions of the filament are then in operation.

In Figs. 3 and 4 the invention has been disclosed. There is a depressible plunger to control the circuits through the filament. More particularly, the incandescent lamp insulation base 12 is formed with a square-shaped opening 12a in which a plunger holding frame 20 is inserted. This plunger holding frame supports an end contact plunger 21. The holding frame 20 comprises a strip of metal which is transversely bent at the areas 20a, 20b, 20c, and 20d. The section between the areas 20a and 20b is formed with an opening through which the plunger contact 21 extends. This contact has a flange 21a limiting its outward motion. An expansion spring 23 is mounted between the flange 21a and the portion of the frame 20 between the areas 20c and 20d. The expansion spring 23 serves to urge the plunger 21 into the extended position.

25 The insulation base 12 is provided with stationary contacts 15' and 16' for controlling the two circuits through the filament similar to the arrangement previously described. These contacts 15' and 16' are arranged upon the walls 30 of the opening 12a. More particularly, the contact 16' is disposed on the end wall and located immediately above the inner end of the plunger 21. The contact 15' is arranged on one side wall and is engaged by the side of the frame 20. The frame 20 maintains its position due to its resiliency. The material of the frame between the areas 20c and 20d is of concave form to produce lateral resiliency so that the sides of the frame naturally hug the walls of the recess 12a. 40 An electric circuit extends from the shell 14 at the point 17a along the lead 17 to the branches 17bb and 17cc. These branches divide the filament 13 into portions; one portion being represented by the numerals 13aa and 13bb, and the 45 other portion by the numerals 13cc and 13dd. The lead 17d connects the filament portions 13aa and 13bb with the end contact 16'. The lead 17e connects the filament portions 13cc and 13dd with the end contact 15'.

50 When the lamp with the socket shown in Figs. 3 and 4 is screwed into the socket in a normal condition, a circuit will exist from the end contact plunger 21 through the filament portions 13cc and 13dd to the shell contact 14. The lamp may be very tightly screwed into the socket so that the plunger 21 is depressed, and in addition to the circuit mentioned, there will be a circuit 55 from the end contact plunger 21 to the contact 16' through the filament portions 13aa and 13bb to the shell contact 14.

In Figs. 5 and 6 another embodiment of the invention has been disclosed in which provision is made so that certain portions or other portions of the filament may be used when desired, or all portions used simultaneously. In this form of the invention there is a stationary frame 30 which is forced into the recess 12a in the insulation base, and which maintains its position due to the flaring construction of its inner extremities engaging similarly shaped side walls of the recess. A rotatable and extendible end plunger 31 is slidably mounted through the central outer portion of the frame 30. A spring 33 normally tends to urge the plunger contact 31 inwards. A pair of arms 31a and 31b set 120°

from each other terminate in finger portions adapted to engage in two of three openings 12b, 12c, and 12d formed in the insulation base. The opening 12b is a dummy opening, while the openings 12c and 12d have stationary contacts 5 16'' and 15'' respectively therein. These contacts connect with the leads and the filament as described relative to Fig. 3 and which are indicated by identical reference numerals.

The end contact 31 may be set in a position 10 in which the fingers of the arms thereof engage in the openings 12b, 12c or 12d in such fashion that one filament portion, or the other filament portion, or both filament portions, are in the 15 electric circuit.

In Fig. 7 another modified form of the invention is illustrated in which a bulb is shown with one end contact 35, and a circuit 36 in connection therewith and with said shell contact 15. This lamp has a filament in the circuit consisting of sections 37a and 37b arranged in parallel. If one section (37a or 37b) burns out the lamp may still be used since the other section functions.

20 While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended 25 claims.

Having thus described my invention, what I 30 claim as new, and desire to secure by United States Letters Patent is:—

1. In an incandescent electric lamp, an insulation base having an axial cavity in its outer end, a shell contact on said insulation base, a pair of contacts within said cavity on the side wall and 40 base wall respectively, a filament for the lamp, an electric lead from said shell contact to an intermediate point on said filament, another electric lead from one end of said filament to one of said pairs of contacts, another electric lead from 45 the other end of said filament to the other of said pairs of contacts, a housing forced within said cavity and bearing against the contact on the side wall thereof, and a spring-pressed contact pin 50 slidably mounted through said housing and having an extended outer end adapted to be pressed inwards to engage the inner end against the contact on the base wall of said cavity.

2. In an incandescent electric lamp, an insulation base having an axial cavity in its outer end, 55 a shell contact on said insulation base, a pair of contacts within said cavity on the side wall and base wall respectively, a filament for the lamp, an electric lead from said shell contact to an intermediate point on said filament, another electric lead from one end of said filament to one of said pairs of contacts, another electric lead from the other end of said filament to the other of said pairs of contacts, a housing forced within said cavity and bearing against the contact on the side 60 wall thereof, and a spring-pressed contact pin slidably mounted through said housing and having an extended outer end adapted to be pressed inwards to engage the inner end against the contact on the base wall of said cavity, said housing comprising a strip of metal bent at several transverse areas and having side portions resiliently 65 engaging against the side walls of said cavity for maintaining itself in position.

3. In an incandescent electric lamp, an insula- 70

tion base having an axial cavity in its outer end, a shell contact on said insulation base, a pair of contacts within said cavity on the side wall and base wall respectively, a filament for the lamp, an 5 electric lead from said shell contact to an intermediate point on said filament, another electric lead from one end of said filament to one of said pairs of contacts, another electric lead from the other end of said filament to the other of said 10 pairs of contacts, a housing forced within said cavity and bearing against the contact on the side wall thereof, and a spring-pressed contact pin

slidably mounted through said housing and having an extended outer end adapted to be pressed inwards to engage the inner end against the contact on the base wall of said cavity, said housing comprising a strip of metal bent at several transverse areas and having side portions resiliently engaging against the side walls of said cavity for maintaining itself in position, the spring of said spring-pressed contact pin being within said housing. 10
